(57) **CLAIM**

The ornamental design for a refrigerating apparatus, as shown and described.

DESCRIPTION

FIG. 6.1 is a left view of the refrigerating apparatus. FIG. 6.2 is a right view of the refrigerating apparatus. FIG. 6.3 is a front view of the refrigerating apparatus. FIG. 6.4. is a back view of the refrigerating apparatus. FIG. 6.5. is a top view of the refrigerating apparatus. The bottom portions of the refrigerating apparatus form no part of the claimed design. The broken lines depict portions of the refrigerating apparatus that form no part of the claim.

1 Claim, 5 Drawing Sheets(56)
